UNITED STATES PATENT OFFICE

ARTHUR ANNESLEY VOYSEY, OF MID HIGHAM, AND HAROLD HERON HOSACK, OF SHORNE, ENGLAND.

APPARATUS FOR BREAKING UP ROADS, &c.

SPECIFICATION forming part of Letters Patent No. 510,738, dated December 12, 1893.

Application filed March 16, 1893. Serial No. 466,306. (No model.) Patented in France March 11, 1892, No. 220,063, and in Belgium March 12, 1892, No. 98,779.

To all whom it may concern:

Be it known that we, ARTHUR ANNESLEY VOYSEY, a resident of Mid Higham, by Rochester, and HAROLD HERON HOSACK, a resident 5 of Shorne, by Gravesend, England, subjects of the Queen of Great Britain and Ireland, have invented certain new and useful Apparatus for Breaking Up Roads and other Surfaces, (for which we have obtained Letters 10 Patent in France, No. 220,063, dated March 11, 1892, and in Belgium, No. 98,779, dated March 12, 1892;) and we do hereby declare that the following is a full, clear, and exact 15 description of the invention, which will enable others skilled in the art to which it app- pertains to make and use the same.

This invention has reference to apparatus for breaking up Macadam roads and analogous surfaces, but particularly Macadam 20 roads; and consists of certain constructions and modes of operating machinery of the kind hereinafter fully specified with reference to the drawings, the novel features concerning which are more particularly specified 25 in the claiming clauses concluding this specification.

The machinery or apparatus according to this invention is adapted to be moved by a road roller or traction engine, or other motor, 30 and the tools (which are mounted in a suitable tool holder or carrier) are rotated on or about their axes which lie in planes running parallel with the direction of motion of the machinery.

35 Figures 1 and 1^a taken together illustrate a side elevation, and Fig. 2 is a plan showing a mechanism according to our invention.

With reference to the drawings, the arrangement therein shown consists, principally, of a motor (namely, a road roller or traction engine,) a frame or carriage connected thereto, and a tool holder, the tools being mounted in shafts or spindles and adapted to be revolved.

45 A designates, generally, the motor, say an ordinary road steam roller or traction engine, of which *a* is the tender or rear tank, *a'* are the hinder road wheels, and *a''* is the fly wheel. *b* are brackets fitting on the sides of the

tank or tender *a*, and secured thereto by bolts 50 and nuts *b'*, said bolts passing through slotted apertures *b²* in *b*, whereby longitudinal adjustment of the brackets (and, as hereinafter described, the drive chain) is obtained. The ends of these brackets form bearings. 55

X generally designates the part of the machinery on which the breaking tools are provided and carried. This machinery comprises side frames *c* connected to the brackets *b* by the shaft *d*, which revolves in the bearings 60 thereof; supporting and running wheels *e* mounted on the outside of *c*; cross rods *f* connecting the two side frames *c* together; bars *g* fixed to the frames *c* for regulating and supporting the tool holder; a movable tool holder frame, adjustable laterally, and consisting of side plates *h*, connecting rods *h'*, and bearings *h²* on the plates *h*; tools *k* mounted in a general tool carrier or holder *i*; a shaft *l* connecting the upper corners of the tool carrier frame plates *h* together; a supporting piece *m* sliding on *l*, and having an upper screwed vertical part *m'* fitted and adapted to rotate therein, and having actuating handles *m²* fixed thereon; a nut *n* (through which 70 *m'* screws) supported and adapted to slide longitudinally in the bars *g*; and a set nut *n'* with handle to tighten and lock the screwed rod *m'* in the nut *n*. The tools *k* are upright or inclined and are rotated axially, (that is, 75 each tool is rotated) and they are fixed in tool holding shafts *k'*, which are supported by, and revolve in, the general holder *i*, and their upper ends are each provided with a spur wheel *k²* meshing with its neighbor, the first shaft *k'* being driven from the shaft *j* by the bevel wheels *k³*, while the shaft *j* itself is driven from the motor A through a sprocket wheel *l* (which may be on the crank shaft of the engine); a pitch chain 2, driven 80 by 1; a sprocket wheel 3, fixed on the shaft *d* and driven by 2; a sprocket wheel 4, also fixed on *d*, and driving the pitch chain 5; a sprocket wheel 6 fixed on the shaft 7, mounted and adapted to rotate in the side frames *c*, 85 and driven by the chain 5; sprocket wheel 8 mounted loosely and adapted to slide on the square shaft 7, and driven thereby; and a 90

pitch chain 10 driven by 8, and driving the sprocket wheel 11, which is fixed upon the tool driving shaft *j*. Thus, in action, when the engine of the roller or traction engine is set in motion and propels the roller, it also rotates the tools *k*.

The breaking of the road or other surface may be effected when the engine is going either forward or backward. This is a considerable advantage.

By adjusting the bearing plates *b* on the tank *a*, any desired tension on the pitch chain 2 can be obtained.

The front part of the frame *c*, as will be seen, are connected to, and the whole mechanism X is propelled by, the roller A from the shaft *d*, while the rear part of the said frame is supported by the wheels *e*; and the frames *c* with the cross rods *f* and bars *g* constitute a carriage or truck. The wheels *e* are mounted practically in the same vertical plane as the axis of the tool holder *i*, or nearly so; by arranging these wheels and tools in this relation to each other, the depth to which the tools *k* enter into the surface of the road, will be the same at all times and in all conditions of its surface, since the contour of the surface of the road is followed by the wheels *e*. As already stated, this mechanism provides for the tool holder and tools being adjusted transversely or laterally. This is done by shifting the tool holder carrier along its supporting rods *f* and moving the nut *n* along the grooved inside edges of the bars *g*, the said nut having rounded sides which slide in the plates. This transverse or lateral adjustment of the tools enables the edges or sides of the road or other surface to be broken.

To lift up the tool carrier, or to lower it onto the ground, the rod *m'* is rotated by the handles *m*²; and it, the rod *m'*, being mounted at its lower end in the piece or block *m*, it passes upward or downward through the nut *n* and so moves the tool carrier up or down. The tool holder plates or frames *h*, when being lifted or lowered move or rock about their supporting rods *f*, the parts of said plates at which the rods *f* pass through them being slotted out as shown by the dotted line at *h*³ to allow of the required amount of movement. It is preferred that in going ahead, the tools should be inclined in the direction of the line marked "Ahead" while for going "astern" they should assume the angle of the line marked "Astern." These positions are fixed by moving the tool holder *i* about on the shaft *j* of the tool holder to the required degree, and then inserting a holding pin through one of the holes *k*⁴ in the side frame *h*, and through a corresponding hole *k*⁵ in the flanges *k*⁶ and *j*² of the tool holder and shaft *j*. In addition to this a key may be driven in into key-ways *k*⁷ in the end of the shaft *j*. This shaft *j* in this case is in two end parts, each being provided with a flange *j*³ which is bolted to the flanges *k*⁶ of the tool holder.

As regards the form of the tools used in the apparatus, these may be of the worm or corkscrew kind as shown, or of pointed fluted form, or plain rectangular shaped tools of any suitable kind may be used. When of screw form they should be arranged to act alternately right and left hand to neutralize side thrust.

In cases where the weight of the road roller or traction engine is not employed to keep the tools in the road surface, the weight of the mechanism is caused to keep the tools in the road surface and is made sufficiently heavy to prevent the tools jumping out of the road, say when they come on particularly hard bits of road. By our invention, to avoid having to raise such a weight off the surface when it is desired to raise the tools out of the ground, the tool carrier is mounted on the main frame or carriage, (which is the heaviest part of the machinery) and is raised thereon without having to lift the whole weight, but at the same time when the tools are lowered, the whole weight of the main carriage or frame, which is supported on its running wheels, comes on the tools to keep them in.

What is claimed in respect of this invention is—

1. In machinery for breaking up Macadam roads or like surfaces, the combination with a frame or carriage connected with and propelled by a motor, of a tool-holder mounted and movable in said frame to set the tools in an inclined position in a forward or backward direction, substantially as described.

2. In machinery for breaking up Macadam roads or like surfaces, the combination with a frame or carriage connected with and propelled by a motor, of vertically adjustable plates carried by said frame, and a tool-holder journaled in said plates and movable on its journals to set the tools in an inclined position in a forward or backward direction, substantially as described.

3. In machinery for breaking up Macadam roads, the combination with a frame or carriage connected with and propelled by a motor, of a tool-holder supported by and laterally adjustable within said frame, substantially as described.

4. In machinery for breaking up Macadam roads, the combination with a frame or carriage connected with and propelled by a motor, of a laterally and vertically adjustable tool-holder supported by said frame, substantially as described.

5. In machinery for breaking up Macadam roads, the combination with a frame or carriage connected with and propelled by a motor of laterally adjustable plates carried by said frame, and a tool-holder journaled and movable in said plates to set the tools in an inclined position in a forward or backward direction, substantially as described.

6. In machinery for breaking up Macadam roads, the combination with a frame or car-

riage connected with and propelled by a motor, of laterally and vertically adjustable plates carried by said frame, a tool-holder journaled in said frame and movable on its journals, rotatable tools carried by said tool-holder, and means for rotating said tools, substantially as described.

In testimony whereof we have hereunto af-

fixed our signatures in presence of two witnesses.

ARTHUR ANNESLEY VOYSEY.
HAROLD HERON HOSACK.
